SCOURING PAD HOLDER

Clarence I. McCall, Waterbury, Conn., assignor of one-half to Milton N. Forde, Naugatuck, Conn.

Application October 8, 1953, Serial No. 384,942

16 Claims. (Cl. 15—209)

This invention relates to holders for scouring pads of steel wool, mesh, woven ribbon, sponges and the like.

An object of the invention is to provide an improved holder for a scouring pad, which is extremely facile in its operation and convenient to use, enabling the pad to be readily manipulated into corners and constricted spaces with great effectiveness and without danger of the material of the pad becoming embedded in the hand of the user.

Another object of the invention is to provide an improved scouring pad holder in accordance with the above which is simple in construction, sturdy, and economical to fabricate.

A further object of the invention is to provide an improved scouring pad holder which may be easily kept clean at all times and wherein there is a minimum likelihood of dirt collecting, to render the holder unsightly or unsanitary.

A still further object of the invention is to provide an improved scouring pad holder in accordance with the foregoing, which securely retains the pad in place and allows most of the pad to be used up before requiring replacement with a new pad.

A feature of the invention resides in the provision of improved and simplified pad-retaining means in a holder as above set forth, which operate to draw up the pad tightly against the holder body when the said means is actuated in pad-engaging direction.

Another feature of the invention resides in the provision of an improved pad holder wherein the actuation of the pad-retaining means may be readily and quickly comprehended by the average housewife or other user.

Other features and advantages will hereinafter appear. In the accompanying drawings, showing several embodiments of the invention:

Figure 1 is a view, partly in side elevation and partly in vertical section, of a pad holder made in accordance with the invention, having a scouring pad attached to it.

Fig. 2 is a front elevational view of the pad holder.

Fig. 3 is a top or plan view of the pad holder.

Fig. 4 is a view like Fig. 1, but showing a modified form of pad-retaining means.

Fig. 5 is a fragmentary vertical sectional view through a pad holder made in accordance with a modification of the invention, the retaining tines being shown in released position.

Fig. 6 is a view like Fig. 5 but with the tines in pad-retaining position.

Fig. 7 is a fragmentary vertical sectional view through a pad holder made in accordance with another modification of the invention, the pad-retaining tines being shown in releasing position.

Fig. 8 is a view like Fig. 7 but showing the tines in pad-retaining position.

Referring to Figs. 1-3, the novel scouring pad holder of this invention comprises a substantially flat base 10 having a somewhat rectangular configuration, characterized by a pair of straight opposite sides 11 and a pair of

2

curved opposite sides 12, providing corners 13. The base 10 obviously may have other outlines than the above, the outline shown being for illustrative purposes. In the interest of economy of material and neatness of appearance, the outline of Fig. 3, is considered desirable; additionally, the provision of the curved sides 12 and corners 13 facilitates the use of the pad in the more inaccessible areas of a kitchenware article.

On the underside of the base 10 a wide and shallow, longitudinally extending groove 14 is provided, having sloping walls 15, said groove preferably extending between the opposite curved walls 12 of the base and being adapted to receive a portion 16 of a conventional scouring pad 17 formed of steel wool or the like.

For reducing curing time where the base 10 is to be molded of plastic, cuts 17a may be incorporated in the undersurface of the base to reduce wall thickness, said cuts communicating with the groove 14 and providing projections which will embed themselves in the pad 17 to minimize slippage thereof.

For the purpose of holding the portion 16 of the scouring pad in the groove 14, thereby to secure the pad to the underside of the base 10, there is provided by the present invention a novel retaining means comprising a pair of curved tines or prongs 18, said tines having inwardly, radially-extending portions 19 secured to opposite ends 20 of a shaft 21 which is carried in a bore 22 of an upstanding handle 23 mounted on the top of the base 10. The handle 23 is preferably flat and disposed directly above the groove 14 in the underside of the base.

Adjacent the four corners 13 of the base 10, slots 24 are provided for receiving the tines 18 whereby the latter may be swung from pad-impaling positions shown in full lines in Fig. 1 to pad-releasing positions shown in dotted lines in this figure. When the tines 18 are in their pad-retaining positions they extend into the slots 24 and across the mouth of the groove 14, and when the tines are in their pad-releasing positions they are retracted from the groove 14 and extend into only one pair of slots 24, that pair located at the right when viewing Figs. 1 and 3.

For the purpose of actuating the tines 18 an extension or arm 25 is provided, said arm preferably being somewhat resilient and yieldable, and being secured to one end 20 of the shaft 21. The arm 25 may advantageously be integral with one of the tines 18 and so arranged that it is aligned with the upstanding handle 23 when the tines 18 are in their pad-impaling positions.

To provide a detent for holding the tines 18 in the pad-retaining positions the handle 23 is made with a groove 26 arranged to receive the arm 25 and to releasably hold the latter in its upright position aligned with the handle. The arm 25 may have its upper extremity bent into the form of a hook 27 to provide a convenient handle adapted to be readily gripped by the user.

It will be understood that with the parts of the holder in the position of Fig. 1 release of the pad 17 is effected by disengaging the arm 25 from the handle 23 and swinging the arm counterclockwise to the dotted line position shown in this figure. The tines 18 will, by this movement, be retracted from the slot 14 and disengaged from the pad 17, enabling the pad to be discarded and a new one put in its place. To accomplish this latter, the new pad is held against the undersurface of the base 10 and the arm 25 swung clockwise to the full-line position of Fig. 1. This will cause the tines 18 to impale the pad and securely hold it to the base.

A modified form of pad-retaining means is shown in Fig. 4. The holder shown in this figure differs from that described above in that modified tines 18a are provided, having straight portions 18b located closer to the shaft end 20 than the remaining curved portions of the tines,

Also, the base 10a of the holder is cut away at 28 to add clearance and enable the straight portions 18b to swing counterclockwise, when the tines are actuated to pad-releasing position, without contacting the base. The advantage of this construction is that, when the pad-retaining tines are actuated from their releasing positions to the pad-retaining positions, the flat portions 18b will pull up the impaled section of the pad 15, thereby holding the scouring pad more tightly to the undersurface of the base 10.

Another modification of the invention is shown in Figs. 5 and 6, depicting a novel shaft and bearing organization by which the scouring pad will be pulled up tightly, as in the form of Fig. 4, when the tines are swung to pad-retaining position.

In Figs. 5 and 6 a handle 23c mounted on a base 10c is provided with a bore 30 having a cross sectional shape somewhat in the form of an inverted heart. In the bore 30 a shaft 31 of rectangular cross section is carried, the shaft mounting the tines 18 and the handle 25, and having surfaces 31a disposed more remote from the axis of the shaft than other surfaces 31b. Shown in Fig. 5 the tines 18 are in released positions and the center of the shaft is relatively low in the bore 30. When the tines 18 are swung to their pad-impaling positions shown in Fig. 6 the shaft 31 will ride up on a camming surface 32 in the bore 30, and will rest on an apex portion 32a of the bore 30 and the center of the shaft will therefore be raised in the bore. This action raises the tines 18 after they have been made to initially penetrate the scouring pad, thereby pulling up the pad tightly against the bottom of the base 10c.

Another modification of the invention by which a similar tightening action of the tines is obtained is shown in Figs. 7 and 8. A handle 23d carried by a base 10d has a circular bore 33 in which a shaft 34 of substantially square cross section is carried. Pad-impaling tines 18 are carried at the ends of the shaft 34 in off-center positions; for example, in Fig. 7 the operating arm 25 which carries one of the tines 18 is disposed below the center of the shaft 34 and the bore 33. When in this position the tines 18 are in readiness to penetrate a scouring pad and as the tines are advanced in their clockwise path they will also be translationally moved or raised so that when in the pad-retaining position of Fig. 8 they will be disposed deeper in the groove 14. In other words, the tines 18 are eccentrically carried by the shafts 34 in such a manner that they are shifted radially toward the center of the bore 33 as they advance through the scouring pad 17. The tines 18 will thus pull the pad 17 tightly against the bottom of the base 10d.

Variations and modifications may be made within the scope of the claims and portions of the improvements may be used without others.

I claim:

1. A holder for a scouring pad, comprising a generally flat base having a groove in its underside adapted to receive a portion of the scouring pad; means for securing said portion of the pad in said groove, including a plurality of curved tines; means including a shaft connected to the tines, disposed substantially at the center of curvature of the tines and carried by the base above the groove thereof, mounting the tines for curvilinear movement on the base laterally of the groove between pad-retaining positions wherein they individually extend entirely across the groove of the base and pad-releasing positions wherein they are retracted from the groove, said tines having their concave sides facing the groove; manually-engageable means for actuating the tines between said positions; and a handle attached to and upstanding from the base, adapted to be grasped by the hands of a user to manipulate the holder and scouring pad secured thereto.

2. A holder for a scouring pad, comprising a generally flat base having a groove in its underside adapted to receive a portion of the scouring pad; means for securing

said portion of the pad in said groove, including a plurality of curved tines; means including a shaft connected to the tines, disposed substantially at the center of curvature of the tines and carried by the base above the groove thereof, mounting the tines for curvilinear movement on the base laterally of the groove between pad-retaining positions wherein they individually extend entirely across the groove of the base and pad-releasing positions wherein they are retracted from the groove, said tines having their concave sides facing the groove; manually-engageable means for actuating the tines between said positions; and a handle attached to and upstanding from the base, adapted to be grasped by the hands of a user to manipulate the holder and scouring pad secured thereto, said means for actuating the tines moving the same simultaneously and including solely one manually-engageable member.

3. A holder for a scouring pad, comprising a generally flat base having a groove in its underside adapted to receive a portion of the scouring pad; means for securing said portion of the pad in said groove, including a plurality of curved tines; means including a shaft connected to the tines, disposed substantially at the center of curvature of the tines and carried by the base above the groove thereof, mounting the tines for curvilinear movement on the base laterally of the groove between pad-retaining positions wherein they individually extend entirely across the groove of the base and pad-releasing positions wherein they are retracted from the groove, said tines having their concave sides facing the groove; manually-engageable means for actuating the tines between said positions; and a handle attached to and upstanding from the base, adapted to be grasped by the hands of a user to manipulate the holder and scouring pad secured thereto, said handle being flat and substantially perpendicular to the base, said manually-engageable means comprising an arm pivoted on the base and carried by said shaft external to and arranged to lie flat with the handle when the tines are in pad-retaining positions.

4. A holder for a scouring pad, comprising a generally flat base having a groove in its underside adapted to receive a portion of the scouring pad; means for securing said portion of the pad in said groove, including a plurality of curved tines; means including a shaft connected to the tines, disposed substantially at the center of curvature of the tines and carried by the base above the groove thereof, mounting the tines for curvilinear movement on the base laterally of the groove between pad-retaining positions wherein they individually extend entirely across the groove of the base and pad-releasing positions wherein they are retracted from the groove, said tines having their concave sides facing the groove; manually-engageable means for actuating the tines between said positions; a handle attached to and upstanding from the base, adapted to be grasped by the hands of a user to manipulate the holder and scouring pad secured thereto; and notched detent means for yieldably holding the pivoted arm in the said position aligned with the handle, said detent means comprising a notch in the handle and said pivoted arm being resilient and engageable in the said notch to retain the arm in aligned position.

5. A holder for a scouring pad comprising a low, broad base having a groove in its underside adapted to receive a portion of the scouring pad, said base having recesses on opposite sides of the groove; a curved tine pivotally mounted on the base for curvilinear movement through one of said recesses between a pad-impaling and retaining position extending across the groove and a pad-releasing position retracted from the groove, said tine having its concave side facing the base and said pivotal mounting being substantially at the center of curvature of the tine, said tine being received in the recesses of the base when extending across the groove and having a supporting arm overlying the base, extending and connected between the tine and the pivotal mounting there-

for; said recesses being located in the path of travel of the tine; an elongate, pivoted manually-engageable means for moving said tine between pad-retaining and pad-releasing positions; and a flat handle attached to and upstanding from the base in substantially perpendicular relation thereto, for engagement by the hands of a user to manipulate the holder and the scouring pad secured thereto, said manually-engageable means lying flat with the handle and against the same when the tine is in retaining position.

6. A holder for a scouring pad comprising a low, broad base having a groove in its underside adapted to receive a portion of the scouring pad, said base having recesses on opposite sides of the groove; a curved tine pivotally mounted on the base for curvilinear movement through one of said recesses between a pad-impaling and retaining position extending across the groove and a pad-releasing position retracted from the groove, said tine having its concave side facing the base and said pivotal mounting being substantially at the center of curvature of the tine, said tine being received in the recesses of the base when extending across the groove and having a supporting arm overlying the base, extending and connected between the tine and the pivotal mounting therefor, said recesses being located in the path of travel of the tine; an elongate, pivoted, manually-engageable means for moving said tine between pad-retaining and pad-releasing positions; a flat handle attached to and upstanding from the base in substantially perpendicular relation thereto, for engagement by the hands of a user to manipulate the holder and the scouring pad secured thereto, said manually-engageable means lying flat with the handle and against the same when the tine is in retaining position; said base having additional recesses on opposite sides of the groove; a second curved tine pivotally mounted on the base, receivable in said additional recesses and extendable across the groove with its concave side facing the base to secure the scouring pad in the groove, said second tine having a supporting arm overlying the base, extending above and connected to the second tine and to the pivotal mounting therefor and being operatively connected with the first tine by a shaft, for simultaneous movement therewith; said shaft constituting said pivotal mountings and carrying said arms at its ends and said handle being disposed between said arms.

7. A holder for a scouring pad comprising a low, broad base having a groove in its underside adapted to receive a portion of the scouring pad, said base having recesses on opposite sides of the groove; a curved tine pivotally mounted on the base for curvilinear movement through one of said recesses between a pad-impaling and retaining position extending across the groove and a pad-releasing position retracted from the groove, said tine having its concave side facing the base and said pivotal mounting being substantially at the center of curvature of the tine, said tine being received in the recesses of the base when extending across the groove and having a supporting arm overlying the base, extending and connected between the tine and the pivotal mounting therefor, said recesses being located in the path of travel of the tine; an elongate, pivoted manually-engageable means for moving said tine between pad-retaining and pad-releasing positions; a flat handle attached to and upstanding from the base in substantially perpendicular relation thereto, for engagement by the hands of a user to manipulate the holder and the scouring pad secured thereto, said manually-engageable means lying flat with the handle and against the same when the tine is in retaining position; said base having additional recesses on opposite sides of the groove; a second curved tine pivotally mounted on the base, receivable in said additional recesses and extendable across the groove with its concave side facing the base to secure the scouring pad in the groove, said second tine having a supporting arm overlying the

base, extending above and connected to the second tine and to the pivotal mounting therefor and being operatively connected with the first tine by a shaft, for simultaneous movement therewith; said shaft constituting said pivotal mountings and carrying said arms at its ends and said handle being disposed between said arms, one of said tines having an extension external to the handle and constituting the means for moving the tine.

8. A holder for a scouring pad, comprising a generally flat base having a longitudinal groove in its underside adapted to receive a portion of the scouring pad; a curved tine; means including a shaft disposed substantially at the center of curvature of the tine and mounting the tine for curvilinear movement on the base transversely of the groove between a pad-retaining position wherein it extends wholly across the groove from one side thereof to the other and a pad-releasing position wherein it is retracted from the groove; manually engageable means for actuating the tine between said positions; and a handle attached to and upstanding from the base, for engagement by the hands of a user to manipulate the holder and scouring pad secured thereto.

9. A holder for a scouring pad comprising a low, broad base having a groove in its underside adapted to receive a portion of the scouring pad, said base having recesses on opposite sides of the groove; a curved tine pivotally mounted on the base for curvilinear movement through one of said recesses between a pad-impaling and retaining position extending across the groove and a pad-releasing position retracted from the groove, said tine having its concave side facing the base and said pivotal mounting being substantially at the center of curvature of the tine, said tine being received in the recesses of the base when extending across the groove and having a supporting arm overlying the base, extending and connected between the tine and the pivotal mounting therefor, said recesses being located in the path of travel of the tine; an elongate, pivoted manually-engageable means for moving said tine between pad-retaining and pad-releasing positions; a flat handle attached to and upstanding from the base in substantially perpendicular relation thereto, for engagement by the hands of a user to manipulate the holder and the scouring pad secured thereto, said manually-engageable means lying flat with the handle and against the same when the tine is in retaining position, said base having additional recesses on opposite sides of the groove; a second curved tine pivotally mounted on the base, receivable in said additional recesses and extendable across the groove with its concave side facing the base to secure the scouring pad in the groove, said second tine having a supporting arm overlying the base, extending above and connected to the second tine and to the pivotal mounting therefor and being operatively connected with the first tine by a shaft, for simultaneous movement therewith; said shaft constituting said pivotal mountings and carrying said arms at its ends and said handle being disposed between said arms said handle being disposed on the top of the base over the said groove; the said shaft passing through and being turnable in the handle, carrying the said tines, said manually-engageable means comprising an operating arm integral with one of said tines extending from the said shaft and movable in an arc between positions parallel with the base and parallel with the handle.

10. A holder for a scouring pad, comprising a substantially flat base having two pairs of corners and a groove in its underside extending midway between said pairs of corners, said base having a handle secured to and upstanding from its top and said handle being disposed over the groove in the base and having in its lower portion a bore extending parallel to the groove, said base having slots adjacent its four corners extending in directions perpendicular to the groove; a shaft passing through and turnable in the bore of the handle; a pair of curved tines secured to the ends of the shaft, said tines normally extending completely through one

pair of slots and being mounted for movement between pad-retaining positions wherein they extend across the groove of the base and through the other slots thereof, and pad-releasing positions wherein they are retracted from the other slots and from the groove; an operating arm projecting laterally from one end of the shaft, for manipulation by a user to turn the shaft and thereby actuate the tines, said handle having a detent notch for receiving said arm to yieldably hold the arm in a given position wherein the tines are disposed in their pad-retaining positions.

11. The invention as defined in claim 10 in which the handle is substantially flat and coextensive with the groove, in which the detent notch is located in an edge portion of the handle, and in which the operating arm is integral with one of said tines and is aligned with the handle when held in the detent notch thereof.

12. A holder for a scouring pad, comprising a generally flat base having a groove in its underside adapted to receive a portion of the scouring pad; means for securing said portion of the pad in said groove, including a plurality of curved tines; means including a shaft connected to the tines, disposed substantially at the center of curvature of the tines and carried by the base above the groove thereof, mounting the tines for curvilinear movement on the base laterally of the groove between pad-retaining positions wherein they individually extend entirely across the groove of the base and pad-releasing positions wherein they are retracted from the groove, said tines having their concave sides facing the groove; manually-engageable means for actuating the tines between said positions; and a handle attached to and upstanding from the base, adapted to be grasped by the hands of a user to manipulate the holder and scouring pad secured thereto, said tines having portions spaced from their pointed ends and offset laterally to occupy positions closer to the bottom of the groove when the tines are in pad-retaining posi-

tions, thereby to pull up the pad into the groove and hold it tightly against the bottom of the base.

13. The invention as defined in claim 1 in which there are means for shifting the tines transversely of their length closer to the bottom of the groove as they are moved from pad-releasing to pad-retaining positions, thereby to pull the scouring pad tightly against the bottom of the base.

14. The invention as defined in claim 6 in which the means for shifting the tines laterally includes an eccentric connection between the tines and the shaft.

15. The invention as defined in claim 1, in which there are means for shifting the shaft laterally upward when it is turned to move the tines from pad-releasing positions to pad-retaining positions, thereby to shift the tines laterally upward as they are advanced through the pad to hold the pad tightly against the base.

16. The invention as defined in claim 15 in which the means for shifting the shaft laterally comprises a camming surface in the bore carrying the shaft, and in which the shaft has portions located further from its axis than other portions and engageable with said camming surface to shift the shaft.
